UNITED STATES PATENT OFFICE

BENJAMIN AUGUSTUS MICHEL, OF NEW ORLEANS, LOUISIANA

REFRIGERATOR

Application filed October 12, 1931. Serial No. 568,478.

The invention relates to a refrigerator and more especially to a sea-food refrigerator.

The primary object of the invention is the provision of a refrigerator of this character wherein sea-food such as fish, crab meat or other sea-food when placed therein will be chilled to maintain the same fresh and when within will be subject to moisture as the drainage from the ice and water container 10 therein will serve to carry off the water content or the meltings from the ice so that the sea-food stored therein will be relieved from excess water accumulation and moisture and thus maintain such food fresh and properly moist.

Another object of the invention is the provision of a refrigerator of this character, wherein the construction thereof is novel in form so that different species of sea-food can be stored therein, such as fish, crabs, shrimp, crab meat or the like and the same will be subjected to a circulation of moisture obtainable from salt water within a compartment therefor, the latter storing ice therein and thus in this manner the sea-food will be maintained fresh, the sea-food being readily accessible when stored for the handling thereof in merchandising.

A further object of the invention is the provision of a refrigerator of this character which is extremely simple in construction, thoroughly reliable and efficient in its purpose, strong, durable, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:—

Figure 1 is a front elevation of a refrigerator constructed in accordance with the invention.

Figure 2 is a sectional view on the line 2—2 of Figure 1 looking in the direction of the arrows.

Figure 3 is a sectional view on the line 3—3

of Figure 2 looking in the direction of the arrows.

Figure 4 is a sectional view on the line 4—4 of Figure 2 looking in the direction of the arrows.

Similar reference characters indicate corresponding parts throughout the several views in the drawings.

Referring to the drawings in detail, the refrigerator comprises a body A formed with an outer wall 10 and a double inner wall 11, these inner walls being suitably spaced apart to accommodate a filling 13 serving as an insulation lining for the body 10.

At the front of the body 10 are arranged upper swinging doors 14 and intermediate doors 15, these being supported upon hinges 16 and are held closed by suitable latches 17. The doors 14 and 15 when open permit access to be had to the interior of the body 10 as is usual in refrigerator construction. In the lower portion of the body 10 and slideable through the front thereof are drawers 18 which are readily accessible on the sliding thereof outwardly through the front of said body. The drawers are supported upon bearing rollers 19 suitably mounted within the body 10 at the bottom and sides of said drawers. Each drawer 18 is preferably fitted with bearing rollers 20 at its side and these are adapted to travel against guide tracks or ledges 21 built within the body 10 and by the employment of said rollers 19 and 20 the drawers will be freely movable for opening and closing thereof.

Within the body 10 rearwardly thereof and coextensive with the major portion of its length is an ice container 22 which opens through the top of said body 10, preferably at two points thereof and these upper ends of said container 21 are closed by removable lids 22 having an insulation lining 23 identical with the lining for the body 10 of the refrigerator. Into this container 21 is adapted to be stored ice with salt applied thereto. The front wall 24 of the container 21 is formed with perforations 25 so that moisture from this container will be emitted into the body 10 for circulation therein and also within the drawers 18. The bottom 26 of

the container 21 is forwardly inclined and at the lowermost portion thereof is arranged a drain spout 27 so that water accumulating within the container 21 will be discharged therefrom through the spout, it being preferable to employ two spouts these being arranged directly over the drawers 18 so that the water in its drainage will discharge into the drawers. The container 21 has supported on its bottom 26 an ice rack 28. The bottom 26 of the container 21 also has extended therethrough a vent tube 29 the same depending within the body 10 rearwardly of each drawer 18 when in closed position and terminates a distance above the bottom of said body 10 of the refrigerator.

Arranged within the body 10 are the shelves 30, these supporting hooks 31 upon which can be hung fish or other sea-food in place within the refrigerator. Immediately above the drawers 18 in the body 10 is a perforated guard or grating 32.

Each drawer is formed with a solid or imperforate bottom 33 and a perforated false bottom 34 elevated from the solid or imperforate body 33, while the back or rear end of each drawer 18 is formed with an opening 35 between the solid or imperforate bottom 33 and the false bottom 34 so that accumulation of water within each drawer will drain off through the opening 35 onto the bottom of the body 10 whence this drainage will be discharged through a drain pipe 36 to without the body 10.

It will be apparent that a circulation of moisture will be continuously had within the body 10 and this moisture is let off from the contents of the container 21 for the ice and brine therein.

The doors 14 and 15 at the front of the body 10 are preferably fitted with glass panels 37 for the display of the contents of the refrigerator and an inspection thereof had before the opening of the same.

What is claimed is:—

1. A refrigerator of the kind described comprising a body having an insulating lining, an ice container arranged therein and having a perforated front and a forwardly inclined bottom, a removable ice rack within the container, a plurality of drawers slidably fitted within the body in its lowermost portion and each having an opening at its rear next to the bottom thereof, a perforated false bottom in each drawer, a reticulated rack within the body above the drawers, a drain spout leading from the container at the lowermost point of the body and directly over each drawer, and air circulating tubes arranged rearwardly of the drawers and opening into the container.

2. A refrigerator of the kind described comprising a body having an insulating lining, an ice container arranged therein and having a perforated front and a forwardly

inclined bottom, a removable ice rack within the container, a plurality of drawers slidably fitted within the body in its lowermost portion and each having an opening at its rear next to the bottom thereof, a perforated false bottom in each drawer, a reticulated rack within the body above the drawers, a drain spout leading from the container at the lowermost point of the body and directly over each drawer, air circulating tubes arranged rearwardly of the drawers and opening into the container, and shelving arranged within the body in superposed relation to each other forwardly of the container.

3. A refrigerator of the kind described comprising a body having an insulating lining, an ice container arranged therein and having a perforated front and a forwardly inclined bottom, a removable ice rack within the container, a plurality of drawers slidably fitted within the body in its lowermost portion and each having an opening at its rear next to the bottom thereof, a perforated false bottom in each drawer, a reticulated rack within the body above the drawers, a drain spout leading from the container at the lowermost point of the body and directly over each drawer, air circulating tubes arranged rearwardly of the drawers and opening into the container, shelving arranged within the body in superposed relation to each other forwardly of the container, and doors arranged at the front of the body and permitting access thereto between the shelving.

4. A refrigerator of the kind described comprising a body having an insulating lining, an ice container arranged therein and having a perforated front and a forwardly inclined bottom, a removable ice rack within the container, a plurality of drawers slidably fitted within the body in its lowermost portion and each having an opening at its rear next to the bottom thereof, a perforated false bottom in each drawer, a reticulated rack within the body above the drawers, a drain spout leading from the container at the lowermost point of the body and directly over each drawer, air circulating tubes arranged rearwardly of the drawers and opening into the container, shelving arranged within the body in superposed relation to each other forwardly of the container, doors arranged at the front of the body and permitting access thereto between the shelving, and hangers arranged beneath the shelving.

In testimony whereof I affix my signature.
BENJAMIN A. MICHEL.
